US00D559232S

(12) **United States Design Patent** (10) **Patent No.:** **US D559,232 S**
Ku et al. (45) **Date of Patent:** **** Jan. 8, 2008**

(54) **WIRELESS HEADSET**

(75) Inventors: **Wen Ku**, Cupertino, CA (US); **Sally Li**, Los Altos, CA (US); **Thomas Chen**, Foster City, CA (US); **Yi-Wen Chen**, Taipei (TW)

(73) Assignees: **Fortimedia, Inc.**, Cupertino, CA (US); **MVOX Technologies, Inc.**, Cupertino, CA (US)

(**) Term: **14 Years**

(21) Appl. No.: **29/275,152**

(22) Filed: **Dec. 15, 2006**

(30) **Foreign Application Priority Data**

Sep. 5, 2006 (TW) 95305023

(51) **LOC (8) Cl.** **14-01**

(52) **U.S. Cl.** **D14/223**

(58) **Field of Classification Search** D14/167, D14/188, 192, 205–206, 217–218, 223, 225; 181/129, 130; 379/430, 431, 446; 381/370, 381/374, 375, 376, 377, 378, 379; 455/569.2, 455/575.9; 224/247, 271; 24/3.11, 35
